US0D1063218S

(12) **United States Design Patent** (10) **Patent No.:** **US D1,063,218 S**
(45) **Date of Patent:** **** Feb. 18, 2025**

(54) **REFLECTIVE VEST**

(71) Applicant: **Yongyue Wang**, Yongkang (CN)

(72) Inventor: **Yongyue Wang**, Yongkang (CN)

(**) Term: **15 Years**

(21) Appl. No.: **29/920,732**

(22) Filed: **Dec. 13, 2023**

(30) **Foreign Application Priority Data**

Jun. 19, 2023 (CN) 202330378929.8

(51) **LOC (15) Cl.** **29-02**
